UNITED STATES PATENT OFFICE.

ISAAC SPRINGER, OF INDIANAPOLIS, INDIANA, ASSIGNOR TO THE INDIANAPOLIS BASKET COMPANY, OF SAME PLACE.

DESIGN FOR A BOX.

SPECIFICATION forming part of Design No. 25,962, dated August 18, 1896.

Application filed June 23, 1896. Serial No. 596,657. Term of patent 7 years.

To all whom it may concern:

- Be it known that I, ISAAC SPRINGER, a citizen of the United States, residing at Indianapolis, in the county of Marion and State of Indiana, have invented a certain new Design in Berry-Boxes, of which the following is a specification, reference being had to the accompanying drawing, which shows a berry-box in perspective of my design.
- 10 The leading feature of my design consists of a four-sided box of greater length than width, and the sides being formed with a cut-away portion extending along the middle of their lower edges.
- 15 A represents the sides of the box, and B the ends, and C is the cut-away portion along the

lower edge of the sides A. This cut-away portion will be provided on both sides and gives to the box an attractive and finished appearance, which gives an increased value 20 to the product offered for sale in them by making the package more inviting to the customer.

What I claim is—

The design for a berry-box, substantially 25 as herein shown and described.

In testimony whereof I affix my signature in presence of two witnesses.

ISAAC SPRINGER.

Witnesses:

JOSEPH A. MINTURN,
FRANK M. TALBOT.
